UNITED STATES PATENT OFFICE.

OLAF NORDBO, OF MALDEN, MASSACHUSETTS.

WINDING AND SHARPENING APPARATUS.

1,407,475.

Specification of Letters Patent. Patented Feb. 21, 1922.

Application filed December 30, 1920. Serial No. 434,058.

To all whom it may concern:

Be it known that I, OLAF NORDBO, a citizen of the United States, and resident of Malden, in the county of Middlesex and State 5 of Massachusetts, have invented an Improvement in Winding and Sharpening Apparatus, of which the following description, in connection with the accompanying drawings, is a specification, like numerals on the 10 drawings representing like parts.

In my present invention I have devised a portable lathe, or winding device, having detachable portions so that it can be readily packed, transported, set up and operated, together with a combined fly wheel and sharpening element. In many lines of wiring and pipe work, it is often necessary to wrap pipes with insulating material, these pipes being secured so closely along the walls, 15 ceilings, or corners, as to be difficult of handling. As the wires, cords or the like used to secure the insulating material come in large balls, which are too large to be passed round and round the piping, it is customary 20 and it is necessary to wind the same on long spindles, usually wooden cores, which has heretofore been done by hand. In such work also the cutting and fitting of the insulating material, using hair felt asbestos, magnesia 25 or the like, constantly and quickly dulls the operators' knives, and consequently these must be continually sharpened during a 30 day's work.

In my present invention I have combined 35 a portable hand operated reel or winding apparatus adapted to fit and hold a wooden core or spindle and on which I wind the wire, cord or string to be used, and also employ a grinding medium which is so fitted 40 and positioned as to constitute the fly wheel or balance wheel of the reel.

Referring to the drawings illustrating a preferred embodiment of the invention,

Fig. 1 is a side view;

Fig. 2 is a cross-sectional view on the line 45 2-2 of Fig. 1;

Fig. 3 is a cross-sectional view on the line 3-3 of Fig. 1; and

Fig. 4 is a fragmentary view of a modification.

As shown in the drawings I prefer to supply a base or standard which may be in the form of a plate or board 1, having a groove or dovetail 2 formed at one end and a similar groove 3 at the other. Adapted to be 55

removably connected in said groove, for example the groove 2 at one end of the board 1, is a slide 4 and a standard 5, the latter carrying journal bearings for a set of gears 6 and 7, with the axle 8 of the upper gear 60 extending outwardly to receive a crank 9 and handle 10, the axle 11 of the lower gear extending inwardly, and carrying a combined fly wheel and grinding element 15, secured between collars or washers 16 and 17, 65 and a retaining nut 18. The shaft 11 preferably extends therethrough and is arranged to receive a removable center 20 fitted in a slot in the shaft and held in position by a cotter pin 21. This center is adapted to 70 take hold of the core or spindle 25 at this end. The entire wheel, gear and crank are supported on the slide 4 and the latter can be moved into position and held rigidly 75 therein by manipulation of a set screw 26. At the other end of the base 1 a similar sliding member 30 carries a post 31 having therein a threaded bushing 32 through which a threaded shaft 33 constituting the other 80 center for the spindle or core 25 is fitted. A nut 34 may lock this shaft in position, which shaft is fitted with a hand wheel 35 for ready manipulation. The slide 30 and block 31 may be fitted toward or from the 85 work to give a quick and ready adjustment for the length of spindle 25 to be operated upon, in addition to the adjustment afforded by the thrust or retraction of the center shaft 33. In order to readily hold the block 31 in position, I may fit a headed bolt 36 90 through the same, having the head 37 housed within a groove 39 in the base of the plate 1, so as to be flush therewith and fit a wing nut 40 on the uppermost portion, thus serving to clamp the block 31 wherever desired. Both 95 the slides 4 and 30 are readily removable and can then be folded into a compact bundle, lengthwise of the plate 1 and the entire apparatus transported and carried by hand from place to place as desired. It can be instantly set up, the slide 4 fitted in position, the set screw 25 tightened to hold the same and the handle 10 operated to actuate the 100 gearing and the grinder 15. When it is desired to reel on the cord, wire or string from the balls in which they come to the spindles or cores 25, the block 31 is fitted, a wooden spindle 25 positioned, the block 31 adjusted, and the shaft 33 also positioned until the 105 spindle 25 is held in rotatable engagement. 110

Thereupon the operator turns the handle 10 and starting the reeling action the same continues automatically.

In order to simplify the arrangement of 5 the adjustable center, I have shown in Fig. 4 a modified form, wherein the adjustable block 31 is bored and instead of fitting a threaded bushing therein, a plain shaft 44 is supplied, having thereon a head 45 and a 10 coiled contractile spring 46, with one end secured in the block 31 as shown at 47, and the other end attached to the head 45 as shown at 48. This contractile spring 46 normally tends to hold the shaft 44 into engagement 15 under the tension of the spring 46 with the spindle 25. A simple longitudinal movement of the shaft 44 outwardly against the tension of the spring 45 serves to remove or to position the spindle 25 and upon release 20 thereof the spring 46 will hold the center 44 in operative and spindle holding position.

It will be seen that my apparatus is portable, can be instantly used as a reel for any suitable length of spindle, while the fly 25 wheel 15 is also a grinder and operators can

sharpen the knives which get dulled so quickly in this work.

My invention is further described and defined in the form of claims as follows:

1. Portable grinding and reeling apparatus of the kind described, consisting in a base, a removable support at one end of said base, carrying an operating handle and a live center, a removable and adjustable support at the other end of said base carrying an adjustable center for the reel and a combined fly wheel and grinder mounted on the live center. 30

2. Portable reeling and grinding apparatus of the kind described, comprising a base, a removable support at one end of said base carrying a grinding medium mounted on a live center and means to rotate the same, in combination with a removable and adjustable support mounted at the other end 35 of the base and provided with a spring pressed center adjustably mounted therein. 40

In testimony whereof, I have signed my name to this specification.

OLAF NORDBO.
